CLAIM

The ornamental design for a roasting rack or the like for
microwave oven, as shown and described.

DESCRIPTION

FIG. 1 is a perspective view of a roasting rack or the
like for microwave oven showing our new design;
FIG. 2 is a front elevational view thereof, the rear eleva-
tional view being a mirror image;

FIG. 3 is a top plan view thereof;

FIG. 4 is a bottom plan view thereof;

FIG. 5 is a right side elevational view thereof, and

FIG. 6 is a left side elevational view thereof.
